MOTORCYCLE LUGGAGE CARRIER

Raymond K. Abrams, Redwood City, Calif., assignor to
Motorcraft, Inc., Redwood City, Calif.

Filed July 10, 1972, Ser. No. 270,251

Term of patent 14 years

Int. Cl. D12—II

U.S. Cl. D12—158

Fig. 1

FIG. 1 is a perspective view of the motorcycle luggage carrier showing my new design;

FIG. 2 is a top plan view thereof;

FIG. 3 is a right side elevational view thereof;

FIG. 4 is a bottom plan view thereof;

FIG. 5 is a rear elevational view thereof; and

FIG. 6 is a front elevational view thereof.

I claim:

The ornamental design for a motorcycle luggage carrier, as shown.
